(57) **CLAIM**

The ornamental design for an ax, as shown and described.

DESCRIPTION

FIG. 1 is an above perspective view of an ax;
FIG. 2 is a below perspective view of the ax;
FIG. 3 is a top view thereof;
FIG. 4 is a bottom view thereof;
FIG. 5 is a left-side view thereof;
FIG. 6 is a right-side view thereof;
FIG. 7 is a front view thereof;
FIG. 8 is a back view thereof; and,
FIG. 9 is a cross-sectional view thereof, taken along the section line indicated in FIG. 6.

The broken lines depict portions of the ax which form no part of the claimed design.

The dot-dash lines shown in FIGS. 1-8 depict a boundary line; the claimed design extends to but does not include the boundary line.

1 Claim, 9 Drawing Sheets
